RAILROAD CROSSTIE AND METHOD OF MAKING THE SAME

Filed Nov. 5, 1929

By Charles Paff
L.D. Underwood Attorney

UNITED STATES PATENT OFFICE

CHARLES PAFF, OF BROOKLYN, NEW YORK

RAILROAD CROSSTIE AND METHOD OF MAKING THE SAME

Application filed November 5, 1929. Serial No. 404,947.

The invention relates to metallic railroad cross ties and a method of making them.

Metallic ties have heretofore been made in various forms but none has come into general use, the tie now generally used being the well known wooden tie. In view of the rapid deterioration of wooden ties and the durability of metal, the failure to adopt metallic ties is obviously due to some defect or defects other than lack of durability. This failure is attributable to the failure to discover a construction which is strong enough to withstand the stresses to which railroad ties are subjected and which, at the same time, may be made at such a cost as to successfully compete in price with the wooden tie. A tie may be constructed of rolled or forged metal which will stand up in use, but such ties are both too heavy to be practical and too costly to manufacture.

The objects of this invention are to provide a metallic railroad tie of comparatively light weight, and which will yet have the strength to meet the most exacting conditions of traffic.

These objects are realized in my invention, of which one of the principal features is the idea of fabricating the tie from thin sheet metal, such as a plate five-thirty-seconds of an inch thick, and concentrating the metal at such points as will cause the whole to constitute a beam, similar to a wooden tie. Another prominent feature of the invention lies in a novel method of procedure whereby the concentration of metal may be effected, and the whole tie constructed, in a very economical way.

The invention will now be described, reference being had to the accompanying drawings illustrating the best form in which I have so far contemplated embodying the invention, in which:

Fig. 1 is a side elevation of the metallic tie of my invention;

Fig. 2 is a top plan view thereof;

Fig. 3 is a vertical longitudinal section on line 3—3 of Fig. 2;

Fig. 4 is a transverse section on line 4—4 of Fig. 3, on an enlarged scale;

Fig. 5 is an end view of a thin metal plate from which the tie is constructed; and

Fig. 6 is an end view of the plate after it has been bent and as it appears prior to the final pressing operation.

55

Referring to the drawings in detail, the tie is of inverted channel form, such as disclosed in my prior Patent No. 1,389,069, dated August 30, 1921, and comprises a horizontal web portion 1, depending vertical side portions or members 2, 2', and flanges 3, 3', projecting laterally outward from the lower ends of the side members. As stated above, the tie is constructed of a thin metal plate. I have found that a successful tie may be constructed from a plate five thirty-seconds of an inch in thickness, and even of less thickness, depending upon traffic conditions to be provided for. By the term "thin," as hereinafter used, I therefore refer to plates which may be successfully bent in rolling mills, approximating the thickness above stated.

A successful tie cannot be constructed of such thin metal if a single plate is merely pressed into tie form in the manner heretofore employed. But I have discovered that a successful tie may be made of such a thin plate if properly reinforced above and below its neutral axis, so as to provide the beam action found in the wooden tie. To carry out this idea, the horizontal web portion of the tie is reinforced from end to end by an additional layer or layers of metal, and a like reinforcement is provided on the opposite side of the neutral axis $a-a$ of the tie. This idea may be embodied in various forms, but in the preferred form this reinforcement above and below the neutral axis is effected by folding a single sheet of metal. As illustrated, the horizontal web 1 comprises a plate 1^a joining the lower arms of two flattened Z-shaped folds 4 and 5, the upper arms of the Z-shaped folds being extended laterally to form the remainder of the web portion of the tie. The Z-shaped folds constitute the required concentration of metal above the neutral axis of the tie. The required concentration of metal below the neutral axis is effected by folding the opposite edges of the plate, and, in the preferred form illustrated, the metal is folded

into four folds to form the two flanges 3, 3', which lie at right angles to the vertical side members 2, 2'. The two upper folds in the flanges are preferably of less width than the two lower folds, thus providing longitudinal shoulders 6, 6', on the flanges 3, 3'. The only purpose of these shoulders is to provide a convenient means to permit the attachment of transverse binding bars 7, which connect the opposed flanges at the ends and center of the tie to prevent spreading or bulging of the vertical side members 2, 2', by excessive tamping of ballast.

The action of a railroad tie is that of a beam in which the part above the neutral axis is under tension and the part below the neutral axis is under compression, except those parts immediately below the rails wherein the stresses are just the reverse. Thus the forces imposed upon the tie tend to shear or crimp it, and in order to prevent this and to secure the same beam action that is present in the wooden tie the metal is provided with a series of corrugations which transmit the superimposed rail stress from the top stress member to the lower stress member. A metallic tie provided with corrugations is shown in my prior Patent No. 1,389,069, but as there shown the corrugations in the side members extend from end to end of the tie and are of equal length throughout. I have found it to be an advantage to omit the corrugations from the central portion of the side members. They are so formed as to have their greatest length immediately below the rails, gradually decreasing in length in opposite directions, as indicated at 8, 8^a, 8^b, 8^c. This arrangement provides the necessary beam action but leaves the central portion of the tie stronger to resist transverse stresses which run through the walls of the tie, this feature being useful particularly when the tie becomes weakened by age or corrosion. This feature is applicable to ties made of forged or rolled sections.

In order to provide a rail-seat for the rail 9, which will give the rail a slight inward cant, a transverse upwardly projecting cant-boss 10, is pressed or otherwise formed in the horizontal web. This feature is likewise applicable to forged metal or rolled sections.

For conveniently inserting ballast beneath the tie, ballast ports 11 are formed at opposite ends thereof, and at the center, as indicated at 12. These ballast ports are formed by slitting the metal to form a tongue and bending it down, by which downwardly and inwardly inclined tongues 13 are provided at the ends of the tie which lie at an angle of substantially 45° to the horizontal axis of the tie, which tend to prevent lateral creeping, and the central portion of the tie is provided with downwardly projecting flanges 14 which prevent the ballast from escaping.

Method.—The tie described above may be

What I claim is:

1. A metallic tie made of a single sheet of metal and comprising a horizontal web portion the central portion of which is composed of a plurality of folds, vertical side members, and a flange composed of a plurality of folds extending laterally from the lower end of each side member.

5 2. A metallic tie as specified in claim 1, in which the folds in the horizontal web portion comprise Z-shaped folds connected together, as shown and described.

10 3. A metallic tie as specified in claim 1, in which the flanges are formed of four folds.

15 4. A metallic tie as specified in claim 1, in which the flanges are formed of four folds, the two lower folds being slightly wider than the two upper folds.

20 5. A metallic tie as specified in claim 1, with the addition of corrugations in the margins of the horizontal web and in the vertical side members.

25 6. A sheet metal tie having a horizontal web portion and vertical sides, the web portion having a central ballast port bounded on two sides by downwardly projecting ballast-retaining flanges.

30 7. A metallic tie of inverted channel form constructed from thin sheet metal, comprising a horizontal web portion, vertical side members, and flanges projecting laterally from the lower ends of the side members, the horizontal web and the flanges each comprising two or more layers of metal.

35 8. A metallic tie of inverted channel form comprising a horizontal web portion and vertical side members, flanges projecting laterally from the lower ends of the side members, and a series of corrugations in the vertical side members at opposite ends of the tie beneath the rail-bearing which are of the greatest length immediately beneath said rail-bearing and gradually decrease in length inwardly toward the center of the tie, leaving the central portion of each side member plane or uncorrugated.

40 9. The method of making a railroad tie from a sheet metal plate consisting in forming longitudinal folds in the plate along the central portion and at the edges, and then subjecting the folded plate to a pressing operation to form it into a tie of inverted channel form comprising a horizontal web portion containing the central fold and depending vertical side members terminating in thickened lateral flanges composed of the marginal folds.

45 10. The method of making railroad ties from a long sheet metal plate consisting in forming longitudinal folds in the plate along the central portion and at the edges, cutting the folded plate into tie-length strips, and then subjecting each strip to a pressing operation to form it into a tie of inverted channel form comprising a horizontal web portion

containing the central folds and depending vertical side members terminating in thickened lateral flanges composed of the marginal folds.

11. The method specified in claim 9 in which a plurality of corrugations are pressed into the strip simultaneously with shaping it into tie form.

Signed by me this 31st day of October, 1929.

CHARLES PAFF.
